UNITED STATES PATENT OFFICE.

JOHN G. SQUIRE, OF NEWCASTLE-UPON-TYNE, ENGLAND.

FURNACE FOR CALCINING COPPER AND LIKE ORES.

1,282,123.

Specification of Letters Patent.

Patented Apr. 9, 1918.

Application filed February 14, 1917. Serial No. 148,472.

To all whom it may concern:

Be it known that I, JOHN GASCOIGNE SQUIRE, a subject of the King of Great Britain and Ireland, residing at 2 East Parade, in the city and county of Newcastle-upon-Tyne, England, have invented new and useful Improvements in Furnaces for Calcining Copper and like Ores, of which the following is a specification.

This invention relates to calcining furnaces, and especially to furnaces for calcining copper and like ores.

The unsatisfactory chemical results usually obtained in the working of the multi-floor copper ore calcining furnaces at present in use are largely due to structural defects and the absence of the conditions necessary for the complete chemical reaction during the calcining operation. These defects may be summarized as follows: firstly, the inefficient control of the temperature during the latter part of the operation; and secondly, an inadequate supply of air to the charge, which consists of a mixture of copper pyrites (ore containing cuprous sulfid) and common salt (sodium chlorid), the insufficient supply of air depriving the charge of the necessary combining proportion of oxygen during the decomposition and causing the burning sulfur to take up oxygen from the surrounding oxids, reducing these to lower oxids; the sulfur thus forms subsalts (sodium sulfite) and reacts with the sodium chlorid to form sub-chlorid (cuprous chlorid, 2CuCl , or sub-chlorid of copper) which is only slightly soluble in water and is difficult to extract in the subsequent lixiviation process. The action is represented by the equation:

The object of the present invention is to provide an improved construction of furnace for calcining copper and like ores free from both the above disadvantages, that is wherein not only is an adequate amount of air supplied to the charge during calcining to highly oxidize said charge and produce cupric chlorid (2CuCl_2) which is very soluble in water and easily and economically extracted

from the charge in the subsequent lixiviation process, thus

but wherein the temperature can be controlled as required, and wherein the calcining chambers are heated in an improved manner and the products of combustion from the fires for heating the furnace are not allowed to enter the calcining chambers, the improved construction insuring more perfect oxidation and chlorination.

A calcining furnace in accordance with this invention comprises a plurality of calcining chambers, and beneath the floor of each calcining chamber I provide concentric flues through which pass the flame and hot gases from fires, said flues being so arranged that they produce concentric heat zones in the floors of the calcining chambers which vary in intensity, and in each of the calcining chambers I provide a rotary air-supplying rabble for distributing, traveling and agitating the charge in the chamber, said rabble having passages and orifices whereby a supply of hot or cold air is led from a central conduit and delivered to the charge in the calcining chambers and mixed therewith, means being provided for controlling said supply of hot or cold air so as to control the temperature in the chambers as required. The rotary rabbles travel the charge through the calcining chambers in such a way that it passes over heat zones of gradually increasing intensity and then over heat zones of gradually decreasing intensity. Air flues are also provided around and beneath the calcining chambers through which air is passed so as to be heated by the waste heat of the furnace, said air forming a hot air supply for the rotary rabbles. Means, such as independent two-way valves, are provided whereby the supply of hot and cold air to each rabble can be controlled independently of the supply to the other rabbles so as to individually control the temperature in each calcining chamber.

Each rotary rabble comprises radial arms carried by a hollow shaft which forms a

conduit and incloses conduits for hot or cold air, said radial arms carrying a series of teeth provided with passages communicating with one of said central air conduits whereby hot or cold air supplied to said conduit is delivered to the charge in the calcining chambers. The teeth of the radial arms are set with their blades at varying angles to their arms. Means are also provided for adjusting the central hollow shaft carrying the rotary rabbles whereby the teeth thereof can be adjusted relatively to the floors of the calcining chambers.

The accompanying drawings illustrate, by way of example, one construction of calcining furnace embodying my invention. In the drawings—

Figure 1 is a central vertical section of the furnace;

20 Figs. 2, 3 and 4 are plan sections, to a smaller scale, on the lines A—A, B—B and C—C respectively in Fig. 1;

25 Figs. 5 and 6 are a part sectional plan and a part vertical section to a larger scale of one of the air supplying rabbles hereinafter described;

Fig. 7 is an elevation of the hub of one of said rabbles;

30 Fig. 8 is a section on the line D—D in Fig. 6;

Fig. 9 is a plan section of one of the teeth of said rabbles;

Fig. 10 is a diagrammatic plan of one of the rabbles;

35 Figs. 11 and 12 are a plan section and a central vertical section illustrating the four two-way valves hereinafter described; and

Fig. 13 is a plan of the base support and means for rotating the central shaft.

40 Referring to the drawings, the calcining furnace therein illustrated comprises three superposed circular calcining chambers 1, 2, 3 (Fig. 1). These chambers are heated by the flame and hot gases from fires 4, provided in the walls of the furnace adjacent to the upper chamber 1 and supplied with hot air. The hot gases and products of combustion from the fires 4 are conducted through concentric heating flues 5 beneath 45 the floor of the upper calcining chamber 1 and pass from the periphery thereof toward the center (as indicated by arrows in Fig. 2) and are then led by vertical and horizontal flues 6 to concentric heating flues 7 beneath 50 the floor of the middle chamber 2 where they again pass from the periphery toward the center (as indicated by arrows in Fig. 3) and are then led by vertical and horizontal flues 8 to concentric heating flues 9 beneath 55 the floor of the lower chamber 3 where they pass from the center toward the periphery (as indicated by arrows in Fig. 4) and are then led away by vertical and horizontal flues 10 which communicate with the main

chimney flue through suitable conduits, as 65 underground passages indicated at 38^a and 10^a between Figs. 4 and 3. It will be seen that in the floor of each calcining chamber concentric heat zones are produced which vary in intensity, said zones gradually increasing in temperature from the center to the periphery of the floor of the upper chamber 1, decreasing in temperature from the periphery to the center of the floor of the middle chamber 2, and decreasing in 70 temperature from the center to the periphery of the floor of the lower chamber 3. It will also be seen that the products of combustion from the fires 4 do not enter any of the calcining chambers 1, 2, 3 so that 75 the charge therein is not contaminated by said products.

Opening out of the upper chamber 1 is an outlet 11 (Fig. 1) which conducts the gaseous or volatile products, sulfur dioxid, 85 cupric chlorid and hydrogen chlorid, from the calcining chambers to the usual condensers.

In each of the calcining chambers 1, 2, 3 I provide a rotary air-supplying rabbble having four hollow radial arms 12 attached to a central hollow vertical shaft 13 which is made in sections and passes through all the calcining chambers. The shaft 13 is supported by a bearing 14 at the top and a 90 footstep bearing 15 at the bottom. The radial arms 12 each carry a series of teeth 16 suitably spaced along the length of the arm. The teeth 16 have horizontal tubular heads 17 (Figs. 6 and 8) from which depend pipes 18 which form the stems of the teeth. The tubular heads 17 and pipes 18 form T-tubes the horizontal members of which communicate one with the other, the horizontal members nearest the hubs 19 of 100 the rabbles communicating with ports 20 (Fig. 6) leading from passages 21 into which open air supply pipes 22 in the interior of the hollow shaft 13. A separate pipe 22 is provided for each rabbble. The 105 heads 17 of the teeth 16 are supported from the radial arms 12 by lateral projections 23 (Figs. 6 and 8) engaging corresponding grooves in the under portions 24 (Fig. 8) of the arms, axial movement of said heads being prevented by set screws 25 (Figs. 5 and 6) bearing on the outermost heads.

The supply of air to the pipes 22 in the hollow central shaft 13 is controlled by three independent two-way valves 26 (Figs. 1, 11 and 12) each adapted to put one of said pipes into communication either with a central hot air supply pipe 27 or with cold air supply passages 28 fed by a blower 29 through a water seal 30. The cold air 120 passes from the blower 29 into the annular chamber 29^a and up through the vertical tubes 29^b into the upper portion of the seal

30 and through openings 29^c therein into the passages 28. This is all shown clearly in Fig. 1. A fourth two-way valve is provided for permitting a supply of cold air 5 to pass from the passages 28 into the hollow central shaft 13 for cooling said shaft. The four two-way valves are arranged 90° apart around the shaft 13. By manipulating the two-way valves 26 hot or cold air can be 10 supplied to the teeth 16 of all or any one of the rabbles, as may be required. The hot air supply pipe 27 communicates at the top through apertures 31 with the interior of the dome-shaped double-sided cap 32 of a 15 hot air seal the base 33 of which comprises a double-sided vessel of U-section containing a refractory powder, which may be iron ore, into which the cap 32 dips, said cap being fixed to and revolving with the shaft 13 20 while the base 33 is stationary. Pipes 34 pass through the refractory powder in the hot air seal 32, 33 and lead hot air from a channel 35 opening out of a hot air supply flue 36, and a valve 37 controls the admission of hot air to the channel 35. The 25 air supplied to the flue 36 is admitted at atmospheric temperature to an air flue in the interior of the main chimney flue and passes up a flue 38 (Fig. 4) to a circumferential air flue 39 beneath the floor of the lower calcining chamber 3 and thence up a flue 40 to a second circumferential flue 41 beneath the floor of the middle calcining chamber 2 and up flues 42 at each side to 35 circumferential flues 43 in the wall of the furnace around the upper calcining chamber 1 which lead the heated air to the fires 4. 44 (Fig. 2) are gas supply flues for the fires. A flue 45 leads from the middle circumferential hot air flue 41 to the hot air 40 supply flue 36. In this way the air employed to aerate the charge in the calcining chambers and for the fires is heated by the waste heat of the furnace. The air to be 45 heated may be propelled by a blower or drawn through the system of flues by natural chimney draft.

The cold air supplied to the central shaft 13 to cool same becomes heated as it passes 50 therethrough and is allowed to enter the upper calcining chamber 1 through apertures 46 (Fig. 1). It may also be allowed to enter all or any of the hollow arms 12 through ports 46^a to cool said arms, the air 55 in the shaft 13, though warm, being at lower temperature than the arms 12.

The aperture 47 in the top of the furnace for the central shaft 13 is closed by an ore seal 48.

60 The teeth 16 of each arm 12 of the rabbles are set with their blades at different angles to those of the adjacent arms. As indicated in Fig. 10, the blades of the set of teeth carried by the arm marked 12^a are

set at such an angle to the axis of said arm 65 as to propel the charge from the center outward toward the circumference of the floor of the calcining chamber when the rabble is rotated in the direction indicated by the arrow; the blades of the set of teeth carried 70 by the arm marked 12^b are set at a reverse angle of the same degree as the blades 12^a so as to return the charge toward the center of the floor of the chamber. The blades of the set of teeth carried by the arm marked 75 12^c are set at such an angle as to drive the charge toward the circumference of the floor of the chamber; while the blades of the set of teeth carried by the arm marked 12^d are set parallel with the axis of said arm so as 80 to merely distribute the charge over the floor of the chamber without exerting any propelling or retracting effect thereon. It will thus be seen that the blades of the arms 12^a and 12^b neutralize each other and their 85 combined effect is to turn over the charge, while the blades of the arm 12^c serve to spread out and further agitate the charge. The blades of the arm 12^d cause the charge to gradually travel from the center toward 90 the periphery of the floor of the chamber. The blades of the rabble teeth are arranged as above described in the upper calcining chamber 1 and gradually travel the charge from the center of that chamber toward its 95 periphery. In the middle chamber 2 the blades 12^a, 12^b and 12^c are oppositely arranged to those in chamber 1 so as to gradually travel the charge from the periphery toward the center thereof. In the lower 100 chamber the blades are arranged in the same manner as in chamber 1 and gradually travel the charge from the center toward the periphery thereof.

The charge of ore to be calcined is delivered in any suitable manner, for example by a screw conveyer 49 (Fig. 1), to a chute 50 which deposits it near the center of the upper calcining chamber 1. The charge is traveled from the center toward the periphery of the floor of the upper chamber 1 by the teeth of the rabble therein, being thoroughly stirred thereby to promote and facilitate the chemical decomposition and to continuously expose free surfaces to the oxidizing influence of the air issuing from the pipes 18 of the rabble teeth, and passes down chutes 51 (Fig. 2) to the periphery of the floor of the middle calcining chamber 2 where it undergoes further stirring 115 and aerating and is traveled by the teeth of the rabble in said chamber toward the center of the floor thereof. From near the center of the floor of the middle chamber 2 the charge is conducted to near the center of 120 the floor of the lower chamber 3 by central chutes 52 and undergoes further agitating and aerating in said chamber and finally

passes from the periphery of the lower chamber by chutes 53 (Fig. 4) to the exterior of the furnace.

It will be seen that the movement of the charge is from the zone of lowest temperature in the floor of the upper calcining chamber 1 to the zone of highest temperature therein, from the zone of highest temperature in the floor of the middle calcining chamber 2 to the zone of lowest temperature therein, and from the zone of highest temperature in the floor of the lower calcining chamber 3 to the zone of lowest temperature therein. The temperature of the charge is thus gradually raised while passing over the floor of the upper chamber 1 and then gradually lowered during its progress over the floors of the middle and lower chambers 2, 3.

20 The central vertical shaft 13 is provided with a spur wheel 54 which is driven by a pinion 55 (Fig. 13) on the shaft 56 of a bevel wheel 57. The bevel wheel 57 is driven by a bevel 58 on a shaft 59 which is 25 rotated by power transmitted from a shaft 60 driven from any suitable source of rotary power.

Suitable means may be provided for driving the central vertical shaft 13 at different speeds if required, and provision is made, by means of a vertical screw 61 under the footstep bearing 15, for the vertical adjustment of the shaft 13 in order to adjust the teeth 16 of the rabbles to the correct 35 distance from the floors of the calcining chambers 1, 2, 3. The vertical screw 61 has fixed on it a worm wheel 62 which is engaged by a worm on a shaft 63 provided with a hand-wheel 64.

40 As will be readily understood, the details of my improved calcining furnace may be considerably modified both in construction and arrangement without departing from the spirit of my invention. For example, 45 the two-way valves 26 controlling the supply of hot and cold air to the rabbles and to the shaft 13, and the hot air seal 32, 33 may be arranged at the top of the furnace, and the hot air flues leading to the channel 50 35 correspondingly modified.

It will now be seen that, by my invention, I provide a calcining furnace wherein an adequate amount of air is supplied to the charge during calcining and intimately 55 mixed therewith, and that the heat is so applied to the floors of the calcining chambers 1, 2, 3 and the charge so traveled over the varying heating zones produced in said floors that the temperature of the charge is 60 gradually increased until the desired temperature is attained and then gradually decreased. The temperature of the floors of the calcining chambers is higher than the temperature of the charge on said floors.

This prevents the sodium sulfate solidifying and the consequent accumulation of a mass of solid sodium sulfate and ore upon the floors, which accumulation occurs where the calcining chambers are heated from above, as is the usual practice, and where the floors are consequently cooler than the charge. In the furnace of the present invention the sodium sulfate solidifies within the charge and is discharged therewith. My improved construction insures the supply of the combining proportion of oxygen to the charge during the decomposition and thus provides a furnace which is essentially oxidizing, producing peroxids and cupric chlorid, allowing of expeditious and economical lixiviation. The silver chlorid is subsequently dissolved in the cupric chlorid and can be recovered. The hot air supplied to the charge is heated by the waste heat of the furnace, and the temperature of the charge can be regulated and controlled by supplying hot or cold air to the calcining chambers as required.

What I claim and desire to secure by Letters Patent is:-

1. A calcining furnace comprising a plurality of superposed calcining chambers, heating flues beneath the floors of said chambers, said flues being substantially horizontally arranged, with certain of the flues, at different distances from a predetermined point on a chamber floor, connected in series so as to produce heat zones of varying intensity in the floor of that chamber, means for introducing a charge to be calcined into said chambers, rotary rabbles in said chambers adapted to distribute, agitate, supply air to and travel the charge over the heat zones in the floors of said chambers, means for supplying air to said rabbles, and means for discharging the calcined charge from said chambers.

2. A calcining furnace comprising a plurality of superposed calcining chambers, heating flues beneath the floors of said chambers, said flues being disposed so as individually to underlie various adjacent portions of a chamber and being connected in series so as to produce heat zones of varying intensity in the floor of that chamber, means for introducing a charge to be calcined into said chambers, rotary rabbles in said chambers adapted to distribute, agitate, supply air to the charge and travel the charge over the heat zones in the floors of said chambers, means for supplying air to said rabbles, and means for discharging the calcined charge from said chambers.

3. A calcining furnace comprising a plurality of superposed calcining chambers, heating flues beneath the floors of said chambers, the flues beneath each chamber being horizontally arranged and connected in se-

- ries, with successive flues so connected arranged different distances from the centers of the chambers whereby heat zones of varying intensity at varying distances from the centers of the chambers are provided, means for introducing a charge to be calcined into said chambers, rotary rabbles in said chambers adapted to distribute, agitate, supply air to and travel the charge over the heat zones in the floors of said chambers, means for supplying air to said rabbles, and means for discharging the calcined charge from said chambers.
4. A calcining furnace comprising a plurality of superposed calcining chambers, heating flues beneath the floors of said chambers said flues being arranged so as to produce heat zones of varying intensity in said floors, means for introducing the charge to be calcined into said chambers, rotary rabbles in said chambers adapted to distribute, agitate, supply air to and travel the charge over the heat zones in the floors of said chambers, means for supplying air to said rabbles, means for discharging the calcined charge from said chambers, means for heating the air supplied to said rabbles, and means for independently controlling said supply of heated air to any one of said rabbles.
5. A calcining furnace comprising a plurality of superposed calcining chambers, heating flues beneath the floors of said chambers said flues being arranged so as to produce heat zones of varying intensity in said floors, means for introducing the charge to be calcined into said chambers, rotary rabbles in said chambers adapted to distribute, agitate, supply air to and travel the charge over the heat zones in the floors of said chambers, means for supplying air to said rabbles, means for discharging the calcined charge from said chambers, air-heating flues adjacent to the calcining chambers by which the air supply for said rabbles is heated, and means for independently controlling said supply of heated air to any one of said rabbles.
6. A calcining furnace comprising a plurality of superposed calcining chambers, heating flues beneath the floors of said chambers said flues being arranged so as to produce heat zones of varying intensity in said floors, means for introducing the charge to be calcined into said chambers, a hollow central shaft passing through all the calcining chambers, a rabble in each calcining chamber carried by said central shaft each rabble comprising radial arms carrying teeth disposed so as to distribute, agitate and travel the charge over the heat zones in the floor of the chamber, air pipes carried by said radial arms, independent air conduits in said central shaft each communicating with the air pipes of one rabble, means for heating air comprising air-heating flues adjacent to the calcining chambers, means for supplying said heated air to each of said air conduits, means for supplying cold air to each of said
- the air pipes of one rabble, means for heating air comprising air-heating flues adjacent to the calcining chambers, means for supplying said heated air to each of said air conduits, means for supplying cold air to each of said air conduits and to the central shaft, means for independently controlling said supplies of hot and cold air to said conduits and central shaft, means for rotating said central shaft, and means for discharging the calcined charge from said chambers.
7. A calcining furnace comprising a plurality of superposed calcining chambers, heating flues beneath the floors of said chambers said flues being arranged so as to produce heat zones of varying intensity in said floors, means for introducing the charge to be calcined into said chambers, a hollow central shaft passing through all of the calcining chambers, a rabble in each calcining chamber carried by said central shaft each rabble comprising radial arms carrying teeth disposed so as to distribute, agitate and travel the charge over the heat zones in the floor of the chamber, air pipes carried by said radial arms, independent air conduits in said central shaft each communicating with the air pipes of one rabble, means for heating air comprising air-heating flues adjacent to the calcining chambers, means for supplying said heated air to each of said air conduits, means for supplying cold air to each of said air conduits and to the central shaft, means for independently controlling said supplies of hot and cold air to said conduits and central shaft, means for rotating said central shaft, and means for discharging the calcined charge from said chambers.
8. A calcining furnace comprising a plurality of superposed calcining chambers, heating flues beneath the floors of said chambers said flues being arranged so as to produce heat zones of varying intensity in said floors, means for introducing the charge to be calcined into said chambers, a hollow central shaft passing through all the calcining chambers, a rabble in each calcining chamber carried by said central shaft each rabble comprising four radial arms spaced 90° apart carrying teeth, the teeth of two of said arms being oppositely inclined, the teeth of the third arm being parallel thereto, and the teeth of the fourth arm being inclined so that said teeth distribute, agitate and travel the charge over the heat zones in the floor of the chamber, air pipes carried by said radial arms, independent air conduits in said central shaft each communicating with the air pipes of one rabble, means for heating air comprising air-heating flues adjacent to the calcining chambers, means for supplying said heated air to each of said air conduits, means for supplying cold air to each of said

air conduits and to the central shaft, means for independently controlling said supplies of hot and cold air to said conduits and central shaft, means for rotating said central shaft, and means for discharging the calcined charge from said chambers.

9. A calcining furnace comprising three superposed calcining chambers, concentric heating flues beneath the floor of the upper 10 chamber adapted to lead hot gases from the periphery toward the center thereof, concentric heating flues beneath the floor of the intermediate chamber adapted to lead said hot gases from the periphery toward the center 15 thereof, concentric heating flues beneath the floor of the lower chamber adapted to lead said hot gases from the center toward the periphery thereof, means for delivering the charge to be calcined onto the floor of the 20 upper chamber near the center thereof, a rotary rabble therein adapted to distribute, agitate, supply air to and travel the charge

toward the periphery of said upper chamber, means for delivering said charge onto the floor of the intermediate chamber near the 25 periphery thereof, a rotary rabble therein adapted to distribute, agitate, supply air to and travel the charge toward the center of said intermediate chamber, means for delivering said charge onto the floor of the lower 30 chamber near the center thereof, a rotary rabble therein adapted to distribute, agitate, supply air to and travel the charge toward the periphery of said lower chamber, means for discharging said charge from said lower 35 chamber, and means for supplying air to said rabbles.

In testimony whereof I have signed my name to this specification in the presence of two subscribing witnesses.

JOHN G. SQUIRE.
